[57] CLAIM

The ornamental design for a fishing lure, as shown and described.

DESCRIPTION

FIG. 1 is a front perspective view of a fishing lure showing my new design;

FIG. 2 is a front elevational view thereof, the rear view comprising a mirror image thereof;

FIG. 3 is a rear perspective view thereof;

FIG. 4 is a right side elevational view taken from a position generally to the right of FIG. 2, the left side view comprising a mirror image thereof;

FIG. 5 is a top plan view thereof;

FIG. 6 is a bottom plan view thereof; and,

FIG. 7 is a longitudinal sectional view taken generally along line 7—7 of FIG. 4.

FIG. 1

FIG. 2

FIG. 3

FIG. 4

FIG. 5

FIG. 7

FIG. 6
